Primary Examiner — Kelley Donnelly(74) *Attorney, Agent, or Firm* — Law Office of Mark Brown, LLC; Christopher M. DeBacker; Mark Brown(57) **CLAIM**

The ornamental design for a caddy, as shown and described.

DESCRIPTION

FIG. 1 is an upper rear perspective view of a caddy showing my new design;

FIG. 2 is an upper rear perspective view thereof;

FIG. 3 is a sectional view thereof taken about the line of FIG. 7;

FIG. 4 is a side elevational view thereof; the reverse side being a mirror image thereof;

FIG. 5 is a front elevational view thereof;

FIG. 6 is rear elevational view thereof;

FIG. 7 is a top plan view thereof; and,

FIG. 8 is a bottom plan view thereof.

The broken lines shown in FIG. 2 indicating a bag as inserted into the bag receiving opening for illustrative purposes only and form no part of the claimed design. The broken lines indicating a gutter for mounting the caddy as shown in FIG. 3 are shown for illustrative purposes only and form no part of the claimed design.
